VARIABLE CAPACITY GEAR PUMP

Arthur P. Heldenbrand, Oklahoma City, Okla.

Application December 5, 1949, Serial No. 131,208

2 Claims. (Cl. 103—120)

1

This invention relates to pumps and, more particularly, but not by way of limitation, to rotary gear pumps.

An important object of this invention is to provide a rotary pump having a variable capacity capable of being minutely controlled from full capacity to zero capacity.

Another object of this invention is to provide a rotary pump which is efficient, durable, simple in construction and may be economically manufactured.

Another object of this invention is to provide a variable capacity rotary pump for use in pumping liquids and which may be used as a hydraulic transmission in trucks, tractors, automobiles, rotary draw works and the like.

Other objects and advantages of the invention will be evident from the following detailed description, read in conjunction with the accompanying drawings, which illustrate my invention.

In the drawings:

Figure 1 is a longitudinal sectional view partially in elevation for clarity.

Figure 2 is a transverse sectional view taken on line A—A of Figure 1 partially in elevation for clarity.

Figure 3 is a transverse sectional view taken on line B—B of Figure 1 with the housing removed.

Figure 4 is an elevational view of the right end of Figure 1 with the housing removed.

Figure 5 is a longitudinal sectional view partially in elevation of a modification of the pump shown in Figure 1.

Figure 6 is a transverse sectional view taken on line C—C of Figure 5 partially in elevation for clarity.

Referring to the drawings in detail, reference character 2 designates a rotary pump having an outer housing 4 and end plates 6 and 8 secured thereto by a plurality of bolts 10.

In the lower portion of the housing 4 are two apertured cylindrical blocks 12 and 14 arranged in spaced relation on the opposite sides of an impeller member 16. The impeller 16 is rigidly mounted on a drive shaft 18 extending through the block 12 and impeller 16, and partially through block 14, and is connected at one end to a suitable prime mover (not shown) for actuating the pump. Also mounted on the shaft 18 is a pinion gear 20 adjacent the outer end of block 12. The blocks 12 and 14 are provided with internal bushings 22 and 24 through which shaft 18 passes. A plurality of ball bearing sets 26 are mounted in circular recesses 28 in the opposite ends of block 12 and in the inner end of

2

block 14 to provide a bearing support for shaft 18. The upper surface of block 12 is concave in configuration and is provided with a longitudinal key seat 30 (Fig. 3) therein, and the upper surface of block 14 is convex in shape and is provided with a transverse groove 32 therein near one end for purposes as will be hereinafter set forth. Suitable packing 34 is provided in a recessed flange 40 in end plate 6 around shaft 18 and is secured therein by a packing nut 36 held by a plurality of bolts 38.

The upper portion of the housing 4 is provided with two apertured cylindrical blocks 42 and 44, arranged in spaced relation on the opposite sides of an impeller wheel 46 rigidly mounted on a sleeve 48. Block 42 is provided with a longitudinal key or projection 50 on the lower surface thereof adapted to move in key seat 30 of block 12. A transverse groove 52 on the outer periphery thereof, terminates on the opposite sides of the key 50 and is adapted to receive a split sealing ring 54. The block 42 is provided with a recessed portion 56 in the outer end thereof for receiving a ball bearing race 58. The block 44 is provided with a tapered bore 60 having a ball bearing race disposed therein. A control shaft 62 extends through end plate 8 and a suitable stuffing gland 64 to a suitable source of manual or mechanical power (not shown) for controlling the longitudinal movement of upper blocks 42 and 44 and impeller 46. A concave lower surface 66 in block 44 cooperates with an upper convex surface of block 14 to permit longitudinal movement between the blocks. The concave surface 66 also permits block 44 to move over gear 16. The outer periphery of block 44 is in continuous contact with a sealing ring 68 retained in a transverse groove 70 in the inner periphery of housing 4 and groove 32 in block 14. The sleeve 48 receives a washer 72 and nuts 74 on the end thereof disposed in bore 60 of block 44 for retaining blocks 42 and 44 and impeller 46 in a proper relation. A male spline 76 (Fig. 2) is provided on the inner periphery of sleeve 48 and is adapted to move in a longitudinal key seat 78 provided in the outer periphery of an auxiliary shaft 80. Although only one spline is shown, it is to be understood that a plurality of splines may be utilized if desired. The shaft 80 is provided at one end with a pinion gear 82 mounted above, and in working engagement with the gear 20 on lower shaft 18. Shaft 80 is also provided with a longitudinal bore 84 extending from the end thereof adjacent end plate 8 to a transverse aperture 86 located in proximity with the inner face of gear 82 for a

purpose hereinafter set forth. A reduced end portion 88 of the shaft receives a washer 90 and nut 92. The end portion 88 is supported by ball bearing 94 retained in a recessed flange 96 of end plate 6 by a cover 98 and plurality of bolts 100.

The end plates 6 and 8 are provided with apertures 102 and 104 respectively for receiving a conduit 106. The housing 4 is provided with an inlet aperture 108 (Fig. 2) substantially media arranged longitudinally in housing 4 (not shown) and adapted to be connected to a source of liquid supply (not shown). An outlet aperture 110 is provided opposite the inlet 108, and receives a conduit (not shown) to the desired point of delivery. A conduit 112 interconnects with conduit 106. The pump 2 is provided with suitable supports 116.

Figures 5 and 6 illustrate a modification of the pump provided with a hydraulic control system having a four-way valve 115 which may be adapted to be operated manually by use of a lever 116 or by a power unit (not shown). The valve 115 is connected to the inlet aperture 108 by a conduit 118, and to the outlet aperture 110 by a conduit 120. Further connection is provided to the aperture 102 in end plate 6 by a conduit 122 and to the aperture 104 in end plate 8 by a conduit 124. It is to be noted that in the modification shown, the longitudinal bore 84 and the transverse aperture 86 in the auxiliary shaft 80 are eliminated.

Operation

In operation the drive shaft 12 is rotated in a counter-clockwise direction (referring to Fig. 2) by any suitable prime mover (not shown), thereby rotating gear 28 and impeller 16 in a counter-clockwise direction and gear 32, shaft 30, and impeller 46 in an opposite clockwise direction.

Assuming the variable capacity gear 46 is disposed as shown in Fig. 1, as long as a constant supply of liquid is present at inlet 108, liquid will be forced by the radial teeth or lobes 128 and 130 on the impellers 16 and 46, respectively, about the inner periphery of housing 4 and displaced through outlet 110. The communication established by conduits 106 and 112 and between outlet 116 and the opposite ends of housing 4 permits the discharge pressure of the supply liquid to be transmitted to the outer end faces 132 and 134 of blocks 42 and 44, respectively, thereby maintaining a liquid seal between the end surfaces of impeller 46, and the outer faces of blocks 42 and 44.

The capacity of the pump may be diminished by reducing the contact surface between impellers 16 and 46. This is accomplished by moving control shaft 62, and hence blocks 42 and 44, and impeller 46 to the left (referring to Fig. 1). It will be apparent that the capacity may be varied as desired by simply moving control shaft 62 longitudinally to the left or right and that the relative lengths of the blocks and impellers may be selected to permit the pump to operate at zero capacity.

As the blocks 42 and 44 and impeller 46 move to the left from the position shown in Fig. 1, the liquid contained in housing 4 adjacent end face 132 of block 42 is transferred by conduit 106 to the end 134 of block 44 in housing 4; and as blocks 42 and 44 and impeller 46 move to the right, liquid contained in housing 4 adjacent end face 134 of block 46 is transferred to the left end 132 of block 42 in housing 4. This transfer of liquid from one end of housing 4 to the other is assisted by bore 84 and aperture 86 in shaft 30 in the preferred embodiment (Fig. 1).

Figures 5 and 6 disclose a modification of the control means and includes a four-way valve 115 having three operating positions. When the valve 115 is in the first position (not shown) a portion 5 of the liquid being pumped flows through outlet conduit 120, the four-way valve 115, and conduit 124 to the end 134 of block 44, thereby forcing blocks 44 and 42 and impeller 46 to the left (referring to Figure 5). Simultaneously liquid contained in the housing 4 to the left of block 42 is 10 discharged through conduit 122, four-way valve 115, and conduit 118 to combine with the liquid being pumped. With the valve in a second position (not shown) a portion of the liquid being pumped flows through conduit 120, four-way valve 115 and conduit 122 to the outer end 132 of block 42, thereby forcing blocks 42 and 44 and impeller 46 to the right. Simultaneously liquid 15 contained in the housing 4 to the right end 134 of block 44 is discharged through conduit 124, four-way valve 115 and conduit 118 to combine with the liquid being pumped. When the valve 20 is in a third position, all communication between conduits 118, 120, 122 and 124 is prevented, therefore, blocks 42 and 44 and impeller 46 are 25 prevented from moving to the left or right by a static fluid lock.

It is readily seen that when it is desired to reduce the capacity of the pump, the four-way valve is set in the first position mentioned above; and to increase the capacity of the pump, the four-way valve is set in the second position above mentioned and to maintain the desired constant capacity of the pump, the four-way valve is set in the third position.

From the foregoing it would be apparent that the present invention contemplates a variable capacity gear pump; wherein the upper impeller 46 and its cooperating blocks 42 and 44 are capable of being independently moved longitudinally relative to the stationary blocks 12 and 14 and the rotating lower impeller 16. Movement of impeller 46 relative to impeller 16 will insure a variance in displacement of the fluid discharging around the inner periphery of housing 4. Furthermore, the concavo-convex relation between block 14 and 44 and the keyway 56 permits sliding movement between the upper blocks and the lower blocks. The concave lower surface 40 permits block 44 to slide over the teeth 128 of impeller 16. The longitudinal movement of impeller 46 may be accomplished either manually 45 or automatically by any suitable type of prime mover, or may be accomplished hydraulically, 50 as is shown in the modification. It will be understood that the invention is not limited to the control means disclosed herein, but may utilize other suitable types if desired.

Changes may be made in the combination and arrangement of parts as heretofore set forth in the specification and shown in the drawings, it being understood that any modification in the precise embodiment of the invention may be made within the scope of the following claims 60 without departing from the spirit of the invention.

I claim:

1. In a rotary pump, a housing, inlet and outlet apertures in said housing, a rotatable drive shaft extending into said housing, an auxiliary shaft in spaced relation to said drive shaft, an impeller on said drive shaft, a second impeller on said auxiliary shaft in engagement with said first mentioned impeller, said second impeller 65 being longitudinally movable on said auxiliary 70 75

shaft, stationary block means mounted on said drive shaft on the opposite sides of said first mentioned impeller, longitudinally movable block means mounted on said auxiliary shaft on the opposite sides of said second impeller, one of said movable block means having a concave side in sliding contact with the adjacent stationary block means providing clearance for the first mentioned impeller upon movement of said movable block means, the other of said movable block means being slidably keyed to the other stationary block means in a direction parallel to the auxiliary shaft, seals around each movable block means providing a seal at each end of the second impeller, valve means, conduit means providing communication between said valve means and the inlet and outlet apertures and the outer ends of said movable block means, said valve means being operative to alternately provide pump discharge pressure on either outer end of said movable block means and simultaneously provide pump inlet pressure to the opposite outer end of said movable block means for moving said second impeller and movable block means longitudinally in variable distances and in either direction.

2. In a rotary pump, comprising a housing, inlet and outlet fluid apertures provided in said housing, a rotatable drive shaft extending into said housing, an auxiliary shaft arranged in vertical spaced relation to said drive shaft, an impeller on said drive shaft, a second impeller on said auxiliary drive shaft in engagement with said first mentioned impeller, said second impeller being longitudinally movable on the auxiliary shaft relative to the first impeller, stationary block means provided on opposite sides of the first impeller, longitudinally movable block means provided on opposite sides of the second impeller, one of said movable block means having a lower concave side in sliding contact with the adjacent stationary block means providing clearance for the first mentioned impeller upon movement of said movable block means, the other of said movable block means being slidably keyed to the other stationary block means in

5 a direction parallel to the auxiliary shaft, seals around each movable block means providing a seal at each end of the second impeller, valve means, conduit means providing communication between said valve means and the inlet and outlet apertures and the opposite outer ends of said movable block means, said valve means being operative in one position to provide pump discharge pressure on one outer end of said movable block means to move said second impeller and movable block means in one direction for decreasing the displacement capacity of the pump, and said valve means operative in another position to provide pump discharge pressure at an opposite end of the movable block means from that of the first mentioned end to move said second impeller and movable block means longitudinally in a direction opposite to the first mentioned direction and provide an increase in 10 the displacement capacity of the pump.
